(57) **CLAIM**

The ornamental design for a bed for magnetic resonance imaging apparatus, as shown and described.

DESCRIPTION

FIG. 1 is a front perspective view of a design for a bed for magnetic resonance imaging apparatus in a raised position. The bed for magnetic resonance imaging apparatus includes a removable compartment on a rear portion of the bed surface, a sliding compartment on a front portion of the bed surface, a flip-up compartment on the front side of the bed and a drawer on each side of the bed.

FIG. 2 is a top view of the bed for magnetic resonance imaging apparatus of FIG. 1 with both the removable compartment and the sliding compartment in closed positions.

FIG. 3 is a left side view of the bed for magnetic resonance imaging apparatus of FIG. 1.

FIG. 4 is a right side view of the bed for magnetic resonance imaging apparatus of FIG. 1.

FIG. 5 is a front view of the bed for magnetic resonance imaging apparatus of FIG. 1 with the flip-up compartment in a closed position.

FIG. 6 is a back view of the bed for magnetic resonance imaging apparatus of FIG. 1.

FIG. 7 is bottom view of the bed for magnetic resonance imaging apparatus of FIG. 1.

FIG. 8 is a front perspective view of the bed for magnetic resonance imaging apparatus of FIG. 1 in a lowered position. The removable compartment, sliding compartment and flip-up compartment are in closed positions.

FIG. 9 is a top view of the bed for magnetic resonance imaging apparatus of FIG. 1 with the removable compartment in an open position where a cover has been removed, and where the sliding compartment is in an open position.

FIG. 10 is an enlarged partial top view of the bed for magnetic resonance imaging apparatus of FIG. 9 with the sliding compartment in an open position; and, FIG. 11 is an enlarged perspective view of the front portion of the bed for magnetic resonance imaging apparatus of FIG. 1 with the flip-up compartment in an open position where the cover extending over the front side of the bed has been flipped up to the top surface. The top surface of the bed for magnetic resonance imaging apparatus has been slid forward exposing a lower opening.

The broken lines illustrate portions of the bed that form no part of the claimed design. The wavy break line shown in FIGS. 10 and 11 indicate the point at which the enlarged view is cut off.
